Inventor:

Axel Andersson
By *Linus Pauling*
Attorney.

UNITED STATES PATENT OFFICE.

AXEL ANDERSSON, OF LUND, SWEDEN.

BOTTLE HOLDER FOR BOTTLE-WASHING MACHINES.

Application filed February 13, 1925. Serial No. 8,974.

To all whom it may concern:

Be it known that I, AXEL ANDERSSON, a citizen of Sweden, residing at Lund, Sweden, have invented a certain new and useful 5
5 Bottle Holder for Bottle-Washing Machines, of which the following is a specification, reference being had to the accompanying drawing.

10 The invention relates to bottle holders for bottle-washing machines of the kind in which the bottles are disposed in inverted position on a horizontal table, revolving step by step.

15 In bottle-washing machines of this kind the cleansing of the interior of the bottles is accomplished by fluids which are supplied, under pressure, from fluid conduits, provided with jet holes or nozzles which are arranged in such a manner that they, when 20
20 the bottle carrying table is at a stand-still, are in line with the mouth of the bottles.

25 In bottle holders of the kind hitherto known the bottles are supported either at the bottle-neck or at the bottle-body, which constructions have the disadvantage that bottles of different dimensions extend differently downwards, so that their mouths may contact with the nozzles on the fluid conduits below them, thereby causing their 30
30 destruction; or the bottles may on the other hand occupy a position so far away from the nozzles of the fluid conduit that the fluid stream becomes ineffective.

According to my invention the bottle 35
35 holders are constructed so as to cause the bottle-mouths to directly rest upon the holder whereby a substantially uniform distance of the mouths of bottles of varying dimensions from the nozzles of the fluid conduit is 40
40 always secured. These new bottle holders consist of a plurality of arms provided at their lower free ends with hook shaped projections, so that the bottle-mouths are left entirely free for the fluid streams directed 45
45 upon them, excepting at the three or four points at which the bottles are supported.

In the accompanying drawing, Figure 1 is a vertical sectional view of the bottle holder according to the invention. Figure 50
50 2 shows the same in a top plan view.

The bottle holder consists of a plurality (three or four) of substantially vertically arranged arms or guides 4, which at their

middle portion are fixed to or integral with the edges of an aperture 12 arranged in the 55 revolving table 2. These arms are at their lower end bent inwards, so that they form hook shaped members, the upper sides of the lower portions of which are adapted to form resting means for the mouth of a bottle, as indicated with dotted lines in Fig. 1. This arrangement offers the advantage compared with other constructions, for example closed and cushioned supporting rings, that the mouths of the bottles and also the necks 60
60 65 of same may freely be subjected to the action of the cleansing fluid streams from underneath.

In practice these bottle holders have been found to be particularly effective, because 70 the bottles may on account of the play between the body of the bottle and the arms, see Fig. 1, be caused to oscillate or rotate by means of the fluid stream acting on the interior of the bottle, whereby the bottles 75 will be cleaned in an ideal manner. These oscillating or revolving movements of the bottle do not appreciably alter the position of the bottle-mouth, which is freely movable in a manner similar to a ball joint on 80 the hook shaped members 13 of the bottle holder, so that the fluid stream is always permitted to freely issue into the interior 85 of the bottle at the same time thoroughly cleaning the whole inner and outer surface of the bottle-mouth.

What I claim and desire to secure by Letters Patent is:—

1. The combination with a horizontally-disposed table having an aperture therein, 90 of a skeleton bottle holder permanently attached to the table and consisting in its entirety of a plurality of substantially-vertical, stationary arms rigidly secured intermediate their ends to the edge faces of the 95 aperture and extending through the latter above and below the table; said arms having their lower ends turned inward to conjointly form a support whereon the edge of the mouth of a bottle in inverted position in the 100 holder may directly rest.

2. The combination with a horizontally-disposed table having an aperture therein, 105 of a skeleton bottle holder permanently attached to the table and consisting in its entirety of a plurality of substantially-ver-

tical, stationary arms rigidly secured intermediate their ends to the edge faces of the aperture and extending through the latter above and below the table; said arms having their lower ends turned inward to conjointly form a support whereon the edge of the mouth of a bottle in inverted position in the holder may directly rest, the arms being spaced from one another an extent sufficient to enable a rocking movement of the bottle therein.

In testimony whereof, I have signed my name to this specification.

AXEL ANDERSSON.
